UNITED STATES PATENT OFFICE

92,967

DESIGN FOR AN ICE CREAM CONE

Sol S. Leaf, Chicago, Ill., assignor to Overland Candy Corporation, Chicago, Ill., a corporation of Illinois

Application July 24, 1933, Serial No. 48,811

Term of patent 14 years

To all whom it may concern:

Be it known that I, Sol S. Leaf, a citizen of the United States, residing at Chicago, in the county of Cook, and State of Illinois, have invented a new, original, and ornamental Design for an Ice Cream Cone, of which the following is a specification, reference being had to the accompanying drawing forming part thereof.

Fig. 1 is a side top perspective view of an ice cream cone;

Fig. 2 is an end elevational view;

Fig. 3 is a top plan view;

Fig. 4 is a bottom plan view.

I claim:

The ornamental design for an ice cream cone as shown.

SOL S. LEAF.
